Primary Examiner — Jennifer Rivard*Assistant Examiner* — Jonathan E Fiencke(74) *Attorney, Agent, or Firm* — Georgi Korobanov(57) **CLAIM**

The ornamental design for a drain plug, as shown and described.

DESCRIPTION

FIG. 1 is a front, right and top perspective view of a drain plug, showing my new design;

FIG. 2 is a rear, left and bottom perspective view thereof; FIG. 3 is a rear, left and bottom perspective view in closed status thereof;

FIG. 4 is a front, right and top perspective view in closed status thereof;

FIG. 5 is a front view thereof;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.

1 Claim, 10 Drawing Sheets(56)
